(57) **CLAIM**

The ornamental design for a light apparatus for firearm, as shown and described.

DESCRIPTION

FIG. 1 is a perspective view of a light apparatus for firearm showing our new design in a state of use as a flashlight; FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the light apparatus for firearm in a state of use as a laser;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines illustrating flashlight and laser components in the drawings depict environmental subject matter that forms no part of the claimed design. All other broken lines depict portions of the light apparatus for firearm that form no part of the claim.
